BACKSPLASH STRUCTURE FOR STOVES

Herman W. Schulze, Elmwood Park, Ill., assignor
to General Electric Company, a corporation of
New York

Application February 6, 1948, Serial No. 6,682

1 Claim. (Cl. 126—214)

1

The present invention relates to electric ranges provided with tilting backsplash structure, and more particularly to improvements in ranges of the character disclosed in the copending application of Leo F. Berg, Serial No. 6,631, filed February 6, 1948, now Patent No. 2,554,083, granted May 22, 1951, and assigned to the assignee of the present application.

The principal object of the present invention is to provide in an electric range including a cooking top and backsplash structure, improved hinge mechanism for mounting the backsplash structure for tilting movement with respect to the cooking top and improved latch mechanism for controlling the position of the backsplash structure.

Another object of the invention is to provide in an electric range of the character noted, improved hinge and latch mechanisms that are arranged positively to eliminate vibratory movement of the backsplash structure with respect to the cooking top when the backsplash structure is latched in a substantially upright normal position and to permit ready movement of the backsplash structure to a forwardly folded operated position after it has been unlatched.

A further object of the invention is to provide in an electric range of the character noted, combination hinge and latch mechanism of improved and exceedingly simple construction and arrangement.

Further features of the invention pertain to the particular arrangement of the elements of the electric range, whereby the above-outlined and additional operating features thereof are attained.

The invention, both as to its organization and method of operation, together with further objects and advantages thereof, will best be understood by reference to the following specification taken in connection with the accompanying drawings, in which Figure 1 is a fragmentary front view of the upper portion of an electric range embodying the present invention; Fig. 2 is an enlarged fragmentary transverse sectional view of the upper portion of the electric range, taken along the line 2—2 in Fig. 1, illustrating the unlatched position of latch mechanism incorporated therein; Fig. 3 is an enlarged fragmentary transverse sectional view of the upper portion of the electric range, taken along the line 3—3 in Fig. 1, similar to Fig. 2, illustrating the latched position of the latch mechanism; Fig. 4 is an enlarged fragmentary side view of the upper portion of the electric range shown in Fig.

2

1, illustrating the normal position of hinge mechanism incorporated therein; Fig. 5 is an enlarged fragmentary side view of the upper portion of the electric range shown in Fig. 1, similar to Fig. 4, illustrating the operated position of the hinge mechanism; and Fig. 6 is an enlarged fragmentary front sectional view of the right-hand upper portion of the electric range, taken along the line 6—6 in Fig. 4, further illustrating the details of the hinge and latch mechanisms.

Referring now to the drawings, the electric range 10 there illustrated, and embodying the features of the present invention, comprises an upstanding frame or body 11 provided with a substantially horizontally disposed cooking top 12 terminating adjacent to the rear thereof in an upwardly directed pedestal 13 carrying upwardly extending backsplash structure 14. The body 11 comprises an oven disposed in the right-hand upper portion thereof below the cooking top 12 and having an open front closed by a suitable door 15, the door 15 being hinged adjacent to the lower edge thereof in a manner not shown and provided with an operating handle 16 positioned adjacent to the upper edge thereof just below the cooking top 12. Also the body 11 comprises a storage space disposed in the left-hand upper portion thereof below the cooking top 12 and receiving a sliding drawer having a front cover 17 that is provided with an operating handle 18 positioned adjacent to the upper edge thereof just below the cooking top 12.

The cooking top 12 merges with the top of the body 11 and terminates adjacent to the rear thereof in the pedestal 13 as previously noted, which pedestal 13 is of hollow construction. Also the cooking top 12 has a plurality of openings formed in the left-hand surface thereof in which corresponding surface heating units are removably secured in place. Specifically, the left-hand surface of the cooking top 12 has four openings formed therein arranged both front and rear and left and right, and removably carrying corresponding surface heating units. For convenience the four surface heating units will be referred to hereinafter as the left front, the right front, the left rear and the right rear surface heating units. In passing it is noted that the left rear surface heating unit may also be lowered below the cooking top 12 in order to provide a deep-well cooking unit. In the drawings, the removable left front and right front surface heating units are respectively illustrated at 19 and 20, the left rear and right

rear surface heating units being hidden by other structure. Also the oven comprises the usual bake and broil heating elements, not shown.

The backsplash structure 14 is of hollow construction and constitutes an instrument and heating control equipment panel, as well as a lamp support arranged to illuminate the cooking top 12. Specifically, the right-hand portion of the backsplash structure 14 carries the instrument and heating control equipment, while the left-hand portion thereof has an opening 21 formed therein in which there is arranged an upwardly and rearwardly sloping light reflector 22, the upper left-hand portion of the backsplash structure 14 constituting a light shade or hood 23 carrying a removable elongated electric lamp 24. Accordingly, the electric lamp 24 when illuminated throws light upon the curved reflector 22, whereby the cooking top 12 is adequately illuminated for cooking purposes. Of course, the backsplash structure 14 also serves the purpose of preventing food cooking in receptacles arranged on the surface heating units from splashing upon the wall of the kitchen in which the electric range 10 is disposed; whereas the upper right-hand portion of the cooking top 12 also serves as a work platform in the preparation and serving of food.

Specifically, the right-hand front surface of the backsplash structure 14 has six openings formed therein and arranged in a lower row and two additional openings formed therein and arranged in an upper row. Four control switches 25, 26, 27 and 28 are respectively arranged in the first four of the lower openings from the left toward the right and respectively control the electric circuits of the left front, the left rear, the right rear and the right front surface heating units. An oven temperature regulator 29 is arranged in the fifth lower opening; and a fifth control switch 30 is arranged in the sixth lower opening and controls the electric circuits of the oven. A timing mechanism 31 is arranged in the left-hand upper opening and controls the opening and the closing of the electric circuits to the oven in accordance with predetermined times; and a timing alarm mechanism 32 is arranged in the right-hand upper opening. This disposition of the instrument and control equipment upon the right-hand front of the backsplash structure 14 provides for ready control of the four surface heating units, as well as the oven.

The backsplash structure 14 is mounted upon the pedestal 13 for tilting movement with respect to the cooking top 12 by an arrangement including two hinge mechanisms 40 and 50 respectively disposed on the left-hand side and on the right-hand side of the range 10 and positioned mutually within the hollow pedestal 13 and the hollow backsplash structure 14. More particularly, the backsplash structure 14 is mounted by the hinge mechanisms 40 and 50 for tilting movement between a substantially upright normal position, as illustrated in Figs. 1 and 4, and a forwardly folding operated position, as illustrated in Fig. 5. When the backsplash structure 14 is moved to its forwardly folded operated position, disposed over the cooking top 12, the over-all height of the range 10 is considerably reduced with respect to the normal height thereof established with the backsplash structure 14 in its substantially upright normal position. This arrangement is very advantageous as the over-all height of the range 10 for crating purposes incident to shipping may be considerably reduced even though

the backsplash structure 14 has a height considerably greater than that normally employed in conventional electric ranges. Accordingly, in the range 10 a high backsplash structure 14 has been provided that is capable of being folded for crating purposes so that the over-all height of the range 10 is equivalent to that of conventional ranges having low backsplash structures.

Preferably the hinge mechanisms 40 and 50 are substantially identical being respectively left and right; and as best shown in Figs. 4 and 5, the right hinge mechanism 50 comprises a stationary section 51 and a movable section 52. The stationary hinge section 51 is substantially L-shaped including a downwardly directed body 53 and an outwardly directed flange 54 suitably secured to the lower surface of a wall 13a of the pedestal 13. Similarly, the movable hinge section 52 is substantially L-shaped including a downwardly directed body 55 and an outwardly directed flange 56 suitably secured to the top surface of a bottom wall 14a of the backsplash structure 14. The bottom wall 14a of the backsplash structure 14 has a large transversely extending opening 14b formed therein; while the top wall 13a of the pedestal 13 has a narrow rearwardly extending slot 13x formed in the right-hand side thereof in alignment with the right-hand end of the opening 14b, whereby the body 55 of the movable hinge section 52 projects through the aligned opening 14b and the slot 13x when the backsplash structure occupies its substantially upright normal position as illustrated in Fig. 4. The downwardly projecting body 55 of the movable hinge section 52 is provided with a forwardly curved arm 57 having an opening formed therein into which a pintle 58 is arranged, the pintle 58 being rigidly secured in an opening formed in the front edge of the body 53 of the stationary hinge section 51.

When the backsplash structure 14 occupies its substantially upright normal position as illustrated in Fig. 4, the bottom wall 14a of the backsplash structure 14 is arranged in superimposed relation with respect to the top wall 13a of the pedestal 13; and the movable hinge section 52 rigidly secured to the backsplash structure 14 occupies its fully downwardly projected position with respect to the stationary hinge section 51 rigidly secured to the pedestal 13. The backsplash structure 14 may be moved from its substantially upright normal position to its forwardly folded operated position by pulling forwardly thereon with respect to the cooking top 12. At this time the movable hinge section 52 rides upwardly and forwardly in the slot 13x formed in the top wall 13a of the pedestal 13 with respect to the stationary hinge section 51; whereby the backsplash structure 14 is tilted or rotated in the counterclockwise direction, as viewed in Figs. 4 and 5. Finally, the body 53 of the stationary hinge section 51 carries a forwardly projecting stop pin 59 adjacent to the front thereof just below the flange 54, which is adapted to engage the inside of the curved arm 57 provided on the body 55 of the movable hinge section 52; thereby positively to limit further tilting of the backsplash structure 14 toward the cooking top 12, as illustrated in Fig. 5. This stop arrangement incorporated in the hinge mechanism 50 positively prevents the instrument and heating control equipment 25, etc., carried on the front of the backsplash structure 14 from striking the adjacent surface of the cooking top 12. The curvature of the arm 57 provided on the body 55 of

the movable hinge section 52 is selected with respect to the position of the pintle 58 carried by the body 53 of the stationary hinge section 51 in order to prevent binding of the lower front edge of the backsplash structure 14 and the upper front edge of the pedestal 13 or undesirable scraping of these adjacent parts over each other incident to tilting movement of the backsplash structure 14.

In view of the above description of the right hinge mechanism 50, it will be understood that the left hinge mechanism 40 is substantially identical except for the reversal of parts, and comprises corresponding elements 41 and 42; the hinge section 41 being rigidly secured to the pedestal 13 and the hinge section 42 being rigidly secured to the backsplash structure 14; all for the purpose previously explained.

Further the range 10 comprises two latch mechanisms 60 and 70 respectively cooperating with the hinge mechanisms 40 and 50 for the purpose of controlling the position of the backsplash structure 14. Preferably, the latch mechanisms 60 and 70 are substantially identical being respectively left and right; and as best shown in Figs. 4 and 6, the right latch mechanism 70 comprises a substantially U-shaped bracket 71 provided with outwardly directed flanges 72 and 73 suitably secured to the lower surface of the top wall 13a of the pedestal 13 adjacent to and toward the left from the right hinge mechanism 50. Also the right latch mechanism 70 comprises an elongated substantially cylindrical latch bar 74 disposed just below the top wall 13a of the pedestal 13 and projecting through two aligned openings 71a formed in the bracket 71. The left-hand end of the latch bar 74 terminates in a downwardly projecting handle 75; and the right-hand end of the latch bar 74 terminates in a gradually tapered or pointed end or nose 76, the center line of the end of the nose 76 being offset upwardly with respect to the center line of the latch bar 74, as clearly indicated in Fig. 6. The nose 76 of the latch bar 74 is arranged to project through two aligned holes 53a and 55a respectively provided in the bodies 53 and 55 of the respective stationary and movable hinge sections 51 and 52 when the backsplash structure 14 occupies its substantially upright normal position. The latch bar 74 is normally biased toward the right in order to force the nose 76 into the openings 53a and 55a when they are arranged in substantial alignment by an arrangement including a coil spring 77 positioned in the bracket 71 and surrounding the portion of the latch bar 74 projecting through the bracket 71. One end of the coil spring 77 bears upon the left-hand side of the bracket 71 while the other end thereof bears against a pin 78 arranged in an opening formed in the latch bar 74 adjacent to the right-hand side of the bracket 71.

When the latch mechanism 70 occupies its normal latched position as illustrated in Fig. 6, the coil spring 77 biases the latch bar 74 toward the right through the holes 53a and 55a, thereby drawing together the two hinge sections 51 and 52 of the hinge mechanism 50 when the backsplash structure 14 occupies its substantially upright normal position. Any tendency of the backsplash structure 14 to vibrate with respect to the pedestal 13 is prevented by virtue of the fact that each time the holes 53a and 55a move toward a position of greater alignment the coil spring 77 thrusts the nose 76 of the latch bar 74 further toward the right thereinto. According-

ly, the tapered nose 76 of the latch bar 74 has a tendency constantly to tighten the closure of the hinge sections 51 and 52 of the hinge mechanism 50 in order further to urge the backsplash structure 14 into its final substantially upright normal position.

In view of the above description of the right latch mechanism 70, it will be understood that the left latch mechanism 60 is substantially identical except for the reversal of parts, and comprises corresponding elements 61, 64, 65, 66 and 67; the latch bar 64 being thrust toward the left by the coil spring 67 acting against the bracket 61 in order to force the nose 66 of the latch bar 64 through the aligned openings formed in the bodies of the respective hinge sections 41 and 42 of the hinge mechanism 40; all for the purpose previously explained.

It is noted that the latch bar 64 of the left latch mechanism 60 is considerably shorter than the latch bar 74 of the right latch mechanism 70; whereby the respectively downwardly directed handles 65 and 75 thereof are arranged to the left of the vertical center line of the range 10 below and respectively offset toward the left and toward the right with respect to the center line of the rear right surface heating unit. The latch mechanisms 60 and 70 normally occupy their latched positions illustrated in Figs. 1 and 3 and when it is desirable to operate them to their unlatched positions illustrated in Fig. 2, the serviceman raises the right rear surface heating unit from the cooperating opening formed in the cooking top 12. At this time the serviceman may reach through the right rear opening formed in the cooking top 12 and seize the handles 65 and 75. When the handles 65 and 75 are then gripped together, the latch bars 64 and 74 are respectively moved toward the right and toward the left from their normal latched positions illustrated in Fig. 3 to their operated unlatched positions illustrated in Fig. 2. At this time the noses 66 and 76 of the latch bars 64 and 74 respectively disengage the hinge mechanisms 40 and 50, whereby the backsplash structure 14 may be operated in either direction with respect to the pedestal 13 in the manner previously explained.

As best shown in Figs. 4 and 5 the top of the body 11 terminates in inwardly directed marginal flanges 91, and the bottom wall of the cooking top 12 and the pedestal 13 terminate in inwardly directed flanges 92, the cooperating flanges 91 and 92 being suitably secured together in order to retain the cooking top 12 and the pedestal 13 in position on top of the body 11. Likewise the top of pedestal 13 terminates in top wall 13a, and the bottom of backsplash structure 14 terminates in the bottom wall 14a, the walls 13a and 14a being arranged to cooperate with each other when the backsplash structure 14 occupies its substantially upright normal position. Since the bottom wall 14a of the backsplash structure 14 is spaced vertically a short distance above the top wall 13a of the pedestal 13 by the hinge mechanisms 40 and 50, a trim 95 is secured to the lower surface of the bottom wall 14a; whereby the trim 95 is positioned between the cooperating walls 13a and 14a when the backsplash structure 14 occupies its substantially upright normal position, thereby to conceal the gap between the backsplash structure 14 and the pedestal 13.

In accordance with the disclosure of the previously mentioned Berg application, flexible electrical wiring is provided in the range 10 and ex-

tends through the hollow pedestal 13 and the hollow backsplash structure 14 in order to interconnect the various instrument and control switches 25, etc., carried on the front of the backsplash panel 14, the surface heating units 19, etc., the oven heating elements, not shown, and a power panel, not shown, carried by the frame or body 11; which flexible electrical wiring extends through an opening, not shown, formed in the top wall 13a of the pedestal 13 and through the opening 14b formed in the bottom wall 14a of the backsplash structure 14, thereby accommodating the tilting movement of the backsplash structure 14 with respect to the pedestal 13. Also it is preferable that a master controller, not shown, be incorporated in this wiring in accordance with the disclosure of the Berg application mentioned; whereby the master controller interrupts the power connections between the power panel and the instrument and control switches 25, etc., carried on the front of the backsplash structure 14, when the backsplash structure 14 is moved from its substantially upright normal position to its forwardly folded operated position.

In view of the foregoing description of the construction and arrangement of the tilting backsplash structure 14, it will be understood that after the range 10 has been installed in a kitchen, the electrical wiring arranged in the hollow pedestal 13 and in the hollow backsplash structure 14, as well as the instrument and control switches 25, etc., carried by the front of the backsplash structure 14 are readily accessible from the front of the range 10 for adjustment and repair; all without moving the range 10 from its installed position in the kitchen. In order to accomplish this end the repairman merely removes the right rear surface heating unit, operates the handles 65 and 75, and then moves the backsplash structure 14 to its forwardly folded operated position disposed over the cooking top 12. At this time a removable cover, not shown, provided on the rear of the backsplash structure 14 may be removed; whereby the interior of the electrical wiring arranged in the hollow backsplash structure 14, as well as the terminals and other mechanical portion of the instrument and control switches 25, etc., are readily accessible from the front of the range 10.

In view of the foregoing, it is apparent that there has been provided an electric range incorporating tilting backsplash structure accommodating compact crating and shipping of the range, as well as ready adjustment and repairs of the instrument and circuit control equipment carried thereby after installation of the range.

While there has been described what is at present considered to be the preferred embodiment of the invention, it will be understood that various modifications may be made therein, and

it is intended to cover in the appended claim all such modifications as fall within the true spirit and scope of the invention.

What is claimed is:

In an electric range including a cooking top, laterally extending backsplash structure arranged adjacent to the rear of said cooking top, said cooking top having an opening therein disposed forwardly with respect to said backsplash structure, a heating unit removably arranged in said opening, and a pair of laterally spaced-apart hinge mechanisms secured to said cooking top and to said backsplash structure for mounting said backsplash structure for tilting movement with respect to said cooking top between a substantially upright normal position and a forwardly folded operated position; the combination comprising a pair of laterally spaced-apart latch members slidably mounted in a concealed position beneath said cooking top and directly below said backsplash structure in its normal upright position, said latch members being arranged intermediate said hinge mechanisms and slidably laterally between inwardly retracted unlatched positions and outwardly extended latched positions, the outer end of each of said latch members being disposed in such a way as to pass when in latched position through a first hole in the stationary portion of the hinge and a second hole in the movable portion of the hinge, thus preventing relative motion between the two hinge portions, said latch member being retractable from the hinge holes in order to release said backsplash structure from its normal upright position into its substantially horizontal operated position, spring means biasing said latch members into their latched position, and a pair of adjacent manually operable handles respectively carried by the inner ends of said latch members and disposed just below and rearwardly of said opening in said cooking top in order to permit convenient simultaneous sliding of said latch members from their latched positions into their unlatched positions against the bias of said spring means by the grasping action of an operator whose arm is inserted through said opening in said cooking top when said heating unit is removed therefrom, such action rendering unnecessary access by the operator to the rear of the range.

HERMAN W. SCHULZE.
